I. F. SUNDERLAND.
REVOLVING DOOR.
APPLICATION FILED AUG. 23, 1916.

1,303,988.

Patented May 20, 1919.

UNITED STATES PATENT OFFICE.

JOHN F. SUNDERLAND, OF NATICK, MASSACHUSETTS.

REVOLVING DOOR.

1,303,988.

Specification of Letters Patent. Patented May 20, 1919.

Application filed August 23, 1916. Serial No. 116,451.

To all whom it may concern:

Be it known that I, JOHN F. SUNDERLAND, a citizen of the United States, and a resident of the town of Natick, in the county of Middlesex and State of Massachusetts, have invented certain new and useful Improvements in Revolving Doors, of which the following is a specification.

The present invention relates to improvements in revolving doors, and particularly such doors of the class known as panic-proof doors, the character of which is that they are collapsible when an unusual pressure is exerted thereon as in a panic. An object of the present invention is to provide such a door which will be automatic and positive in its action, simple and reliable in construction and will dispense with the use of straps, cables, bars and the like as have been heretofore employed, and in which the collapsing mechanism will be inclosed within a comparatively small compass, forming an un conspicuous part of the door.

With these and other objects in view my invention is shown in the accompanying drawings, and will be hereinafter more fully described with reference thereto and finally pointed out in the claims.

In the accompanying drawings,

Figures 1, 1^a and 2 are diagrammatic views, showing the closed or normal position of the doors, a position with two of the doors locked and the other two swinging, and the collapsed or open position, respectively.

Fig. 3 is a plan view of the upper side of the top disk or plate and also the lower side of the bottom disk, showing the door in normal or closed position.

Fig. 4 is a similar view showing two of the doors collapsed, and in dot and dash lines the doors folded in pairs.

Fig. 5 is a sectional view taken along the line 5—5 of Fig. 3.

Fig. 6 is a plan view of the under side of the top disk and the upper side of the bottom disk, and showing the doors in a similar position to that shown in Fig. 4.

Fig. 7 is a sectional view along the line 7—7 of Fig. 3, and

Fig. 8 is a fragmentary view of a slightly modified form of construction in which the door is capable of being released from the locking means.

Similar reference characters indicate corresponding parts throughout the several figures of the drawings.

Referring to the drawings, my improved door comprises a center shaft 10, and four revolving wings 11, radially disposed about the said shaft. Disks 12, revolvable about the central axis, are provided both at the top and the bottom of the door, Figs. 3 and 4, representing a top view of the upper disk and a bottom view of the lower disk. For convenience the description will be confined to the top portion of the door, the lower portion being exactly the same, but in reversed position. On the upper side of the said disk there is provided a large square geared portion 13, raised from the disk, and spaced from the edges of the said geared portion there are provided slots or grooves 14, forming a square about the said squared gear. To each of the wings 11 is secured rigidly at each end (top and bottom) a hanger 15 which is forked or recessed, as at 16, to straddle the disk, and disposed within the recess and rigid with the hanger (and therefore with the wing) there is arranged a geared disk 17 which engages the teeth of one side of the large square gear 13 and to which is attached an axial pin 18 which engages and turns in a rectangular shaped shoe 19 slidable in the slot 14. As the geared disk 17 rolls on the square geared portion 13 (under conditions specified hereinafter), the pin 18 rigid with said disk 17 will turn in the shoe 19, and the latter will slide in the groove or slot 14.

Upon the under side of the upper disk 12 there are provided four small disks 20 whose axes are parallel to the shaft 10, and are located midway between the ends of the slots 14 and centrally thereof. These disks and the large square gear are rigid with the disk 12, and may be integrally formed therewith. In the lower surface of each of the disks 20 there are provided six grooves 21 radiating

from the center. Below each of the disks 20 there is provided a disk 22, of corresponding size, rotatable upon a pin 23 screwed into the disk 20. A single ridge 24 provided 5 on the upper face of the disk 22 is adapted to fit into one of the grooves 21 of the disk 20, the said disk 22 being held against the disk 20 by means of a spring 25 disposed upon the pin 23 and inclosed within a sleeve 10 or casing 26 surrounding the pin. The ridge 24 as well as the grooves 21 are semi-circular in cross section, it being understood that each ridge 24 is straight and radial with reference to its disk 22. The tension of the spring may 15 be regulated by turning the pin 23, by means of the screw head 27. The disk 22 is provided with a recess 28 extending inwardly from the periphery thereof, which in normal position of the wings is engaged by a pin 20 29 carried by the wing. The construction at the lower end of the door as above pointed out, is exactly like the above described construction, but in inverted position.

The operation of the door is as follows: 25 During the ordinary use of the door the wings and disks revolve upon the shaft in the well known manner. The resilient engagement of the disk 22 with the disk 20 is of such strength as to maintain the doors 30 rigid, against the pressure exerted thereon during the normal use thereof. Should any unusual pressure be applied, as for instance in a panic by a number of persons forcing themselves against the two inner wings as indicated by the arrows (Fig. 1), the pins 29 disposed within the recesses 28 exert a similar pressure upon the disks 22 forcing the ridge 24 out of engagement with the groove 21, against the pressure of the spring 25, thereby permitting the wing to turn with respect to the disk 12, the ridge 24 dropping into the next groove 21. The geared disk 17 rolls along the square gear, forcing the shoe 19 along in the slot 14 while the pin 18 turns 45 in said shoe. The inner wing may continue to be thrown around into a collapsed position parallel with the other collapsed wing, the pin 29 leaving the recess 28, the shoe 19 traveling as far as slot 14 permits. The 50 wing will remain in its collapsed position until considerable pressure is applied to it in the opposite direction, to return it to its normal position. The collapsed position is indicated in Fig. 2, and at one side of Figs. 55 4 and 6. The disk 22 remains in its shifted position (near a corner of the square gear 13) until the wing is brought around again toward its normal position, when the pin 29 will again engage the recess 28 and continued pressure upon the wing will force the ridge 24 to leave the groove into which it has fallen. The disk 22 will turn on the pin 23 until the wing has again assumed its normal position, when the ridge 24 will again

become seated in the groove 21 which is 65 radially disposed with respect to the large disk 12.

In Fig. 4 I have shown in dot and dash lines, the manner in which the wings may be folded in pairs. When thus folded, it will 70 be noted the ridge 24 is seated in one of the grooves 21, thereby preventing the wings from returning to their normal position unless unusual pressure is brought to bear upon them. This holds the four wings 75 rigidly without the use of bars, straps or other such holding means.

In the form shown in Fig. 8, the pin 29 is arranged in a socket 29^a of the wing in which the same may be raised and lowered by means of a pin or handle 29^b working in a slot 29^c provided in the wall of said socket, so that said pin 29 may be brought into or out of engagement with the holding plate or disk 22, at the recess 28. It will be understood that when the pin 29 is disengaged from the wing, the latter may swing independently of the holding mechanism. In this way two of the wings may be used as moving wings, as illustrated in Fig. 1^a, the other two wings being bolted to the ceiling by bolts *x. y.* the bolting of these wings holding the disk 12 rigid.

In the present invention, it will be seen, both a simple and reliable construction are 95 provided which dispenses entirely with the necessity for cables, shafts, bars, or the like. The parts of the device are practically out of view and permit of a light weight door entirely free of the mechanical encumbrances of most doors of this type. 100

I have illustrated preferred and satisfactory forms of my invention, but it is obvious that changes may be made therein within the spirit and scope thereof, as defined in 105 the appended claims.

I claim:

1. In a revolving door, a revolving support, a plurality of wings normally radiating from said support and connected therewith to swing relatively thereto, plates mounted to turn on said support about axes parallel to that of the support, and also movable lengthwise of said axes, springs tending to force said plates lengthwise of 110 their axes toward said support and into holding engagement therewith, and co-operating means on the wings and on the respective plates, normally in engagement to connect the wings with said plates, but adapted to be brought out of engagement to release the wings. 115

2. In a revolving door, a plurality of wings normally radiating from a common axis and provided with gears which are 120 rigid with the respective wings, a support mounted to revolve about said axis and provided with a polygonal gear in mesh with 125

the several wing gears, means for keeping said wing gears in mesh with the polygonal gear as they roll along it, and spring-pressed means located at the central portion 5 of each of the sides of the polygonal gear for normally holding the wings rigid with said support, in positions extending through said central portions and through said axis.

3. In a revolving door, a revolving support provided with a polygonal gear, a plurality of wings normally radiating from the axis about which the support revolves, and provided with gears in mesh with said polygonal gear, means for keeping said wing 15 gears in mesh with the polygonal gear as they roll along it, and means located at the central portions of the sides of the polygonal gear for normally locking the wings to the revolving support in positions in which said 20 wings extend from the support at the central portions of the polygonal gear.

4. In a revolving door, a revolving support provided with a polygonal gear, a plurality of wings normally radiating from the 25 axis about which the support revolves, and provided with gears in mesh with said polygonal gear, means for keeping said wing gears in mesh with the polygonal gear as they roll along it, said support being further provided with a series of intersecting 30 grooves for each of said wings, the points of intersection being adjacent to the central portions of the sides of the polygonal gear, plates mounted to turn on said support about axes passing through said points of 35 intersection, and each provided with a rib adapted to fit said grooves, and also provided with a slot extending outwardly to the periphery of such plate, and each of the 40 wings being provided with a pin normally within said slot but adapted to slip out of it, and springs for pressing the respective plates against the grooved surfaces of the revolving support.

45 5. In a revolving door, a central pivot, a plurality of wings radiating from said pivot, a revolving supporting plate for said wings, means pivotally connecting said wings to said supporting plate, a spring-pressed plate for each of said wings rotatably secured to said supporting plate and provided with yieldable holding means, and means carried by said wings connecting said wings with said rotatable plates, said spring- 50 pressed plates adapted to hold said wings rigid with said supporting plate during ordinary pressure on said wings, unusual pressure on said wings adapted to move said holding means into non-holding position to 55 permit collapsing of said wings.

6. In a revolving door, a revolving support provided with a polygonal gear, a plurality of wings normally radiating from the axis about which the support revolves, and

provided with gears in mesh with said polygonal gear, means for keeping said wing gears in mesh with the polygonal gear as they roll along it, plates mounted to turn on said support about axes parallel to that of the support, and also movable lengthwise of 65 such axes, mating rib and groove formations on the contacting surfaces of said plates and of said support, springs tending to force said plates lengthwise of their axes toward the support, and coöperating means on the 70 wings and on the respective plates, to cause the latter to be turned on their axes and release the corresponding wings under unusual strain.

7. In a revolving door, a revolving support provided with a polygonal gear and a slot surrounding the gear, slides mounted to travel in said slot but held against turning, wings pivoted to said slides about axes parallel to that of the support, gears coaxial 80 with the wing pivots and rigidly secured to the respective wings, and in mesh with the polygonal gear of the support, and means located at the central portions of the respective sides of the polygonal gear, for normally locking the wings to the support in radial positions extending from the respective central portions.

8. In a revolving door, a revolving support, a wing connected with said support 95 and adapted to swing about an axis parallel to that of the support, a plate mounted to turn on the support about an axis coinciding with that of the wing, said plate being also movable lengthwise of its axis, mating rib 100 and groove formations on the contacting surfaces of said plate and said support, a spring tending to force said plate toward the support, and coöperating means on the wing and on the plate to normally lock the 105 wing to the support, but cause the plate to be turned and the wing to be released under unusual strain.

9. In a revolving door, a revolving support provided with a guideway, a slide movable along said guideway, a wing pivoted to said slide about an axis parallel to that of the support, a plate pivoted to said support about an axis which coincides with that of the wing in a certain position of the wing, 110 said plate being also movable lengthwise of its axis, and spring-pressed toward the support, coöperating means on the contacting surfaces of the support and of said plate to normally lock the plate to the support, and 115 coöperating means on the wing and on said plate to normally couple the wing to said plate, yet allow them to become disconnected, and the wing to swing on its pivot relatively to the support when the wing is 120 subjected to an unusual strain.

10. In a revolving door, a revolving supporting plate provided with a polygonal

gear on one of its sides, locking means on the other side of said plate, a plurality of wings normally radiating from the axis about which said plate revolves, and provided with gears engaging the said polygonal gear on one side of the revolving plate, and with means for engaging said locking means on the other side of said plate, and means for keeping said wing gears in

mesh with the polygonal gear as they roll along it.

In testimony, that I claim the foregoing as my invention, I have signed my name in presence of two subscribing witnesses.

JOHN F. SUNDERLAND.
